DEVICE FOR REMOVING LIQUID FROM FILAMENTARY STANDS

Filed May 10, 1949

UNITED STATES PATENT OFFICE

2,648,965

DEVICE FOR REMOVING LIQUID FROM
FILAMENTARY STRANDSCharles W. Cox, St. Albans, W. Va., assignor to
American Viscose Corporation, Wilmington,
Del., a corporation of Delaware

Application May 10, 1949, Serial No. 92,286

8 Claims. (Cl. 68—241)

1

This invention relates to an apparatus for continuously expressing a liquid from a running bundle of filamentary material. The apparatus is particularly useful in removing a liquid from large textile strands such as a rayon tow comprising up to 150,000 or more separate filaments.

It is an object of the invention to provide an adjustable apparatus for removing a substantial portion of the liquid carried by such strands. Another object is to provide apparatus which may be instantly threaded or from which the strand may be removed without severing it or stopping the movement of the strand. It is another object to remove liquid materials from large running strands by apparatus which has but little area coming into contact with the strand and the liquid, thereby avoiding the untidiness and maintenance associated with the operation of liquid-expressing means such as squeeze rolls. Still another object is to provide the apparatus with readily replaceable and abrasion-resistant elements which constitute the portions of the apparatus which are subjected to wear and abrasion from the passage of strand thereover. Another object is to provide an apparatus for removing liquid material from two or more strands simultaneously that may be adjusted readily to obtain a different degree of liquid removal. Other objects, features and advantages of the invention will be apparent from the following description of the invention and the drawing relating thereto in which

Fig. 1 is an elevation view partly in section of an embodiment of the invention;

Fig. 1A is a section view of the apparatus illustrated in Fig. 1 taken along line II—II;

Fig. 2 is a pictorial view of the apparatus illustrating a stationary support therefor and its relationship with a pair of running strands;

Fig. 3 is a section of a modified apparatus taken along line III—III of Fig. 4;

Fig. 4 is a section taken along line IV—IV of Fig. 3; and

Fig. 5 is an enlarged section taken along line V—V of Fig. 1 illustrating in greater detail a portion of the apparatus and its relationship with a multiple-filament strand.

In brief, the invention comprises an apparatus provided with one or more U-shaped or bi-prong members through each of which a continuous filamentary bundle may be passed. Each member is rotatable on an axis substantially parallel to the longitudinal direction of its oppositely spaced strand-guiding surfaces. When there are two or more members in the apparatus, the mem-

bers are simultaneously rotatably adjustable about their axes.

One embodiment of the invention is illustrated in detail in Figs. 1 and 2. As shown in Fig. 2, the apparatus 8 extends through a frame support 9 with the branched members 14 and 15 thereof extending into the region traversed by the running filamentary bundles or strands 11 and 12. The strands pass between the legs or prongs of the members 14 and 15 which are secured to the lower end portions of shafts 16 and 17, respectively. These shafts extend through housings 19 and 20 into a case 22. Gears 24 and 25 are secured to the portions of the shafts extending into the case by means of such as keys 26 and set screws 27. The gears are provided with suitable teeth for engagement with the worm gear 28 secured onto a shaft 29 which extends through the wall of the case 22 as shown in Fig. 1A. A hand wheel 30 is secured to the portion of the shaft 29 which extends outwardly from the case. The sleeve members 31 which rest on flanges 33 and 34 extending radially inwardly, respectively, from the lower end portions of the housings 19 and 20, and the flanges 32 of bearings 36 correctly align the ears 24 and 25 with the worm gear 28 in a vertical direction. Bearings 36 and 37 support the shafts laterally within the sleeves 31.

The case 22 may be formed in any desired manner, preferably so that easy access is obtained to the mechanism therewithin. As shown, it consists of a cylindrical shell 40, a lower disc portion 41, and an upper disc portion 42, said disc portions fitting within the annular recesses 44 and 45 of the shell 40. The case, as illustrated, is held together by bolts 46 extending through the plate 42 to the plate 41. The case is secured to the frame member 9 by lugs 47 and cap screws 43.

Normally, it will be desired to have the forked members 14 and 15 rotate in such a manner as to maintain equal angularity with the general direction of the paths of the strands 11 and 12. It is permissible by other gear arrangements to rotate these members in the same direction. However, in the devices shown, adjacent members are rotated in opposite directions with respect to each other.

On account of the tendency of the strands, particularly when the strands contain slurry-like liquids containing finely divided solid materials, to wear away or abrade the surface with which the strand comes into contact, the surfaces 51, 51a, and 51b of the forked members are protected with replaceable wear-resisting elements 48 which may be inserted into holes 49 drilled into

the members 14 and 15 and having sufficient diameter to permit insertion of the rod-like elements 48. In order that the elements may be more readily removed from the holes 49, smaller holes 50 are drilled into the members contiguously and coaxially with the holes 49 to permit insertion of means such as a small punch which may be gently tapped to loosen an element 48, if the need arises. The holes 49 have threaded sections near the other ends thereof to accommodate small exteriorly threaded plugs 52. This method of retaining replaceable inserts will be found to have wide applicability in strand-guiding devices. It will be noted that the members 14 and 15 are not duplicates but, on account of their opposite directions of rotation, are mirror images of each other. In the event they turned in the same direction, the bifurcate members are constructed as duplicates.

The elements 48 are produced in rod-form from an abrasion or wear-resistant material such as glass, quartz, sapphire, or other material which is also preferably corrosion-resistant. Rather brittle materials, if they are sufficiently abrasion-resistant, may be utilized for this purpose even though the elements 48 are subjected to appreciable sidewise pressure from a tow or other strand as it passes through the member 14 or 15 since the elements 48 are laterally reinforced by portions 54 and 55 of the member 14 or 15. These portions are provided with arcuately formed surfaces 57 and 58 (Fig. 5) which fit around the portions of the elements 48. A horizontal element 48 is provided across the upper portions of the members 14 and 15 since the forked members are ordinarily positioned at a level lower than the strand would assume if it was tightly stretched, and the strands tend to pass along the upper portions of the openings 59 through the members 14 and 15. Although the end portions of the legs of the members 14 and 15 are provided with lugs or toes 60 to prevent the tow from over-running, spreading, or perchance escaping from the inner surfaces of the members, the upper surfaces 61 of the toes are subject to less wear and need not be provided with special wear-resistant materials such as the elements 48.

The use of worm gears to transmit adjustment or rotation from the shaft which is manually or otherwise rotated, to the shafts which support the pronged members is advantageous because of the self-locking operation which results from the low power transmission efficiency of worm gearing. The gears should be selected with a sufficiently small helix angle of the worm so that any force applied to the elements 14 and 15 tending to rotate the shafts 16 and 17 will be overcome by the friction force caused by engagement of the gears.

Figs. 3 and 4 diagrammatically illustrate an apparatus suitable for handling four separate strands. The apparatus is similar to that of Figs. 1 and 2 except that modification has been made to accommodate additional shafts 65 and 66. As the gears 68 and 69 are suitable for meshing only with the worm gear 70, spur gears 72 and 73 secured on shafts 75 and 76 respectively, in mesh with gears 77 and 78 on shafts 65 and 66, respectively, transmit the drive needed for simultaneous adjustment of the forked members 78. The arrangement shown in Figs. 3 and 4 is merely illustrative of the manner in which a plurality of shafts may be interconnected to obtain simultaneous adjustment of a plurality of bifurcate

liquid stripping members. As illustrated in Fig. 1, right and left-handed members are provided on the apparatus according to the direction in which they are rotated.

While preferred embodiments of the invention have been shown, it is to be understood that changes and variations may be made without departing from the spirit and scope of the invention as defined in the appended claims.

10 I claim:

1. An apparatus for stripping a liquid from multiple-filament strands comprising a plurality of similarly aligned bifurcate members having parallel axes of rotation extending in a direction generally parallel to the longitudinal direction of the opposed inner surfaces of the members, parallel shafts extending from the members, intermeshing gear members connecting the shafts for rotation in unison, a manual controller, and a worm gear drive connecting the controller with at least one shaft for turning all of the members simultaneously.

2. An apparatus for stripping a liquid from multiple-filament strands comprising two rotatable U-shaped members each having an axis of rotation and being similarly aligned with respect thereto, said axes extending in a direction parallel with the longitudinal direction of the inner laterally spaced surfaces of the legs of each member, said inner surfaces being normally in engagement with opposite sides of the strand, a housing, two parallel shafts each extending into the housing from the closed end of one of the members, a shaft extending transversely through the casing between the shafts of the members normal to a plane containing said shafts, a gear fixed on each shaft on the portion thereof extending within the housing, a single worm gear on the transverse shaft in mesh with each of the gears mounted on the shafts of the members.

3. An apparatus for stripping a liquid from multiple-filament strands comprising two similarly aligned bifurcate members having parallel axes of rotation which extend in a direction generally parallel to inner laterally spaced surfaces of the legs of each member, a housing, two parallel shafts each extending along an axis of rotation from the closed end of one of the members into the housing, a gear secured to each shaft on the portion thereof extending into the housing, a shaft extending transversely through housing between the gear normal to a plane containing the axes of the parallel shafts, a hand wheel fixed to a portion of the transverse shaft outside of the housing and a worm gear fixed to the transverse shaft in mesh with the gears of the parallel shafts.

4. An apparatus for stripping a liquid from multiple filament strands comprising a plurality of bifurcate members having parallel axes of rotation extending in a direction generally parallel to the longitudinal direction of the opposed inner surfaces of the members, shafts extending from the members concentrically along respective axes of rotation, gear members on adjacent shafts connected in driving relationship for rotating the shafts together, and a manual controller in drive connection with one of said gear members for turning all of the shafts simultaneously.

5. An apparatus for stripping a liquid from multiple filament strands comprising a plurality of bifurcate members having parallel axes of rotation extending in a direction generally parallel to the longitudinal direction of the opposed

inner surfaces of the members, shafts extending from the members concentrically along respective axes of rotation, gear members on adjacent shafts connected in driving relationship for connecting the shafts for rotation together, said gear members comprising a pair of worm gears and a worm extending transversely therebetween and in mesh therewith, said worm gears being mounted on separate adjacent shafts in a substantially common plane, and manually operable means connected with the worm for turning it.

6. An apparatus for stripping a liquid from multiple filament strands comprising a plurality of bifurcate members having parallel axes of rotation generally parallel to the longitudinal direction of the opposed inner surfaces of the members, parallel shafts extending from the members, gear members in series meshing relationship for connecting the shafts for rotation in unison, a manual controller, and a worm gear drive comprising one of said gear members connecting the controller with at least one shaft for turning all of the members simultaneously.

7. An apparatus for stripping a liquid from multiple filament strands comprising a plurality of bifurcate members having parallel axes of rotation extending in a direction generally parallel to the longitudinal direction of the opposed inner surfaces of the members, shafts extending from the members concentrically along respective axes of rotation, gear members on adjacent shafts in driving relationship for connecting the shafts for rotation in unison, means for

manually turning all of the shafts simultaneously, and means for leading strands along separate paths, each path extending between the legs of one of the members, each leg of a member comprising an abrasion-resistant element extending along the surface of said opposing surfaces that is leading with respect to the direction of rotation of the member to which the said surface belongs about its axis.

10 5 15 10 15 20 3. Apparatus as defined in claim 7 wherein the abrasion resistant element consists of an elongate insert, and each leg of the members has a pair of holes disposed at each end of said surface edge complementary to the peripheries of opposite end portions of the insert, one of the holes being open at both of its ends to permit passage therethrough of the insert to the other hole.
